UNITED STATES PATENT OFFICE.

ERNEST AUBREY BUTLER AND WILLIAM ANGELO NICHOLS, OF TORONTO, ONTARIO,
CANADA.

LEVELING DEVICE.

1,254,574.

Specification of Letters Patent. Patented Jan. 22, 1918.

Application filed April 14, 1916. Serial No. 91,217.

To all whom it may concern:

Be it known that we, ERNEST A. BUTLER and WILLIAM A. NICHOLS, subjects of the King of Great Britain, residing at Toronto, in the Province of Ontario and Dominion of Canada, have invented new and useful Improvements in Leveling Devices, of which the following is a specification.

This invention relates to leveling devices, and one object of the invention is to produce a device of simple and improved construction whereby a spirit level may be arranged at various predetermined angles with respect to its support, enabling such level to be used not only for ascertaining the angles of inclination, but also for enabling a predetermined angle to be maintained during the progress of work, such as grading and the like.

20 A further object of the invention is to produce a simple and improved attachment which may be readily applied to a straight edge or templet to coöperate with the same in ascertaining angles of inclination during the progress of work.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing—

Figure 1 is a side elevation showing a portion of a straight edge to which the device has been applied.

45 Fig. 2 is a top plan view of the same.

Fig. 3 is a transverse sectional view taken on the line 3—3 in Fig. 1.

Fig. 4 is a sectional view partly in elevation of a spirit level to which the principles 50 of the invention have been applied.

Corresponding parts in the several figures are denoted by like characters of reference.

The improved device, as seen in Figs. 1, 2 and 3, embodies a casing or housing formed 55 of sheet metal or other material sufficiently

stiff and durable for the purposes of the invention, said housing comprising a top wall 15, side walls 16 and braces 17 terminally connected with said side walls which are thereby stiffened and reinforced, said 60 braces also constituting supports whereby the housing may be mounted on a straight edge or templet, shown at 18. The side walls 16 are provided with bosses 19 through which clamping screws 20 are threaded, said 65 screws serving to engage the side faces of the straight edge for the purpose of mounting the housing in position securely and yet detachably so that said housing may be readily disassembled from the straight edge 70 for convenience in packing and transporting the same.

The top wall 15 of the housing has a longitudinal slot 21, and the side walls 16 are provided with bearings for a transverse 75 shaft 22 carrying at one end a thumb piece 23 which is threadedly connected therewith and whereby it may be turned about its axis. The other end of the shaft 22 carries a hand or pointer 24 which may be secured thereon 80 by means of a thumb screw 25, it being obvious that by loosening the thumb screw the pointer may be adjusted about the axis of the shaft 22. The shaft 22 carries intermediate the ends thereof a slotted casing 26 85 containing a spirit level 27, said casing being capable of being partly projected through the slot 21, as indicated in dotted lines in Figs. 1 and 3.

It will be readily seen that when the improved device is mounted on a straight edge, the casing containing a spirit level, as well as the hand or pointer 24, is capable of being independently adjusted. Thus the spirit level may be positioned in parallel relation to the straight edge or at any desired angle with respect thereto. One side wall 16 of the device carries one or more scales for co-operation with the hand or pointer 24; thus there may be a scale of degrees, a scale of 90 inch fall to the foot, a scale of feet fall in fifty feet, a scale adapted to railroad grades, or any other scales for special purposes. By the construction described, after the adjustment of the spirit level with respect to the 95 straight edge, the hand or pointer may be adjusted with respect to any one of the scales, at zero or at any other desired point, although the pointer will usually be set at zero after proper adjustment of the spirit 100 105 110

level. In using the device it is obvious that any deviation from the desired inclination may be ascertained by turning the shaft carrying the spirit level and the pointer until the spirit level is in a horizontal position, when the pitch or inclination will be indicated on the scale with respect to which the pointer has been set.

In the form of the invention illustrated in Fig. 4, the body member 30 designates the body of an ordinary spirit level in which a casing 31 of approximately semi-cylindrical form has been fixed in a suitable recess or mortise, said casing having an axial bearing for a shaft 32 carrying a spirit level 33 contained in a suitable casing 34, said shaft carrying also at one end thereof a hand or pointer 35 which is adjustable about the axis of the shaft, being held in position by means of a thumb nut 36. One end wall of the housing 31 carries a scale 37 for coöperation with the hand or pointer, said scale having been devised with special reference to the requirements of some particular trade for the special use of which the implement is manufactured. The top portion of the housing 31 has a slot 38 through which the casing of the spirit level may be partly projected. The operation of this device is identical with that previously described, except that being of smaller dimensions only a

single scale is provided for coöperation with the hand or pointer 35.

Having thus described the invention, what is claimed as new, is:—

1. The combination with a straight edge, of a housing having a longitudinally slotted top wall and side walls, one of which has a scale marked on its outer face, a transverse shaft, a casing carried by the transverse shaft and containing a spirit level, said casing being adapted to be projected through the longitudinal slot in the top wall of the housing, and a pointer fixed adjustably on the shaft for coöperation with the scale.

2. In a device of the class described, a housing having side walls, a longitudinally slotted top wall and transverse braces terminally connected with the side walls, means for securing said housing on a straight edge, a scale on the outer face of one of the side walls, a shaft supported for rotation in the side walls, a casing carried by said shaft and containing a spirit level, said casing being adapted to be projected through the longitudinal slot in the top wall of the housing, and a pointer fixed adjustably on the shaft for coöperation with the scale.

In testimony whereof we affix our signatures.

ERNEST AUBREY BUTLER.
WILLIAM ANGELO NICHOLS.
